US00D739092S

(12) **United States Design Patent**
Bogart(10) **Patent No.:** **US D739,092 S**
(45) **Date of Patent:** **** Sep. 15, 2015**(54) **LIVESTOCK FEEDER**

(71) Applicant: **Mark Bogart**, Joshua, TX (US)
 (72) Inventor: **Mark Bogart**, Joshua, TX (US)
 (**) Term: **14 Years**
 (21) Appl. No.: **29/520,293**
 (22) Filed: **Mar. 12, 2015**
 (51) LOC (10) Cl. **30-03**
 (52) U.S. Cl.
 USPC **D30/121**

(58) **Field of Classification Search**

USPC D30/133, 121, 122, 124, 127, 128, 132, D30/131, 114, 119; 119/51.01, 61, 51.04, 119/53, 57.91, 54, 53.5, 52.4, 51.11, 63, 119/61.2, 52.1, 57.5, 57.6, 51.13, 62, 75, 119/500, 501, 521, 57.92, 59, 51.12, 57.1, 119/56.1, 57; 239/7, 687, 379, 397.5; 222/199, 181.1, 181.2, 185.1, 557, 222/156, 485, 486, 548, 555; 220/200, 227, 220/247, 262; 221/174, 185.1, 289, 295, 221/296, 559; 454/35; 209/270, 283, 244; 52/194, 192; 49/279, 344, 357; D34/28

(57) **CLAIM**

The ornamental design for a "livestock feeder," as shown and described.

DESCRIPTION

FIG. 1 is a perspective view of a livestock feeder, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
